UNITED STATES PATENT OFFICE.

EDWARD MCCLINTOCK, OF ST. PAUL, MINNESOTA.

INTERLOCKING RELAY.

No. 879,885.

Specification of Letters Patent.

Patented Feb. 25, 1908.

Application filed April 30, 1907, Serial No. 371,051.

To all whom it may concern:

Be it known that I, EDWARD MCCLINTOCK, of St. Paul, Ramsey county, Minnesota, have invented certain new and useful Improvements in Interlocking Relays, of which the following is a specification.

The object of my invention is to provide an interlocking relay for operating signals on a single track electric road.

My invention consists generally in providing a relay mechanism whereby the signal will be operated when the train is moving in one direction and will be silent or inoperative when the train is moving in opposite direction.

In the accompanying drawings, forming part of this specification, Figure 1 is a diagrammatic view illustrating the normal position of the relay. Fig. 2 is a similar view illustrating the position assumed by the mechanism upon the entrance of a train into the block. Fig. 3 is a diagrammatic view illustrating the relay when the train has passed out of the insulated section and entered the second or contiguous one. Fig. 4 illustrates the position of the relay when a train enters the block from the right and moving in the opposite direction from the trains illustrated in the previous figures.

In the drawing, A represents an insulated rail section and B a similar contiguous section separated from one another and the other rails on the same side of the track by suitable insulation I. These rail sections are on the same side of the track to adapt the device for use on electric roads where the rails on one side are used for the return of the current.

L is a conductor leading to a suitable signal indicated by S.

D represents a battery.

2 is a relay having an armature 3 connected with a similar armature 4 by a link 5.

6 is a second relay having a conductor 7 leading to the track rail 8 opposite the insulated section B, and a conductor 9 leads from the relay 6 to said section B, and said section B and the rail 8 are connected with the battery D. The relay 6 has an armature 10 and similar armatures 11 and 12 are provided, connected with the armature 10 by a bar 13. A conductor 14 connects the armature 10 with the armature 3 and a conductor 15 leads from the conductor 14 through the battery F to the insulated rail section A. A conductor 16 extends from each side of the battery F

and the relay 2. A contact point 17 is in the path of the armature 3 and has a conductor 18 leading to the rail 8. A contact point 19 is provided in the path of the armature 4 and 60 has a conductor 20 leading to the ground G. A conductor 21 connects the armature 4 with the armature 11. A contact point 22 is in the path of the armature 10 and has a conductor 23 leading to the rail 8 and a contact 65 point 24 is in the path of the armature 11 and is connected with the conductor L leading to the signal. A contact point 25 is in the path of the armature 12 and has a conductor 26 leading to the insulated rail section B and 70 the armature 12 is also connected with the conductor 15 by a conductor 27.

The circuit will normally be closed through the relay 2 by means of battery F and conductors 15 and 16, whereby the armature 3 75 will be attracted and the circuit opened at the points 17 and 19. The circuit through the relay 6 will also be closed by means of conductors 7 and 9, rail 8, battery D and insulated rail section B. The armature 10 will 80 be thereby attracted and the circuit opened at the point 24 or the one connected with the signal line.

Referring now to Fig. 2 particularly, we will assume that a train has passed on to the 85 insulated section A coming from the left. The battery F will be instantly short circuited and the current instead of passing through the relay 2 will pass through conductor 14, armature 10, conductor 23, rail 8, 90 truck of the locomotive and conductor 15 back to the battery. The relay 2 will be thereby deenergized and its armatures will drop to the position indicated in Fig. 2 and contact with the points 17 and 19 whereupon 95 the battery F will be short circuited through conductor 15, armature 3, conductor 18, track rail and the locomotive truck. Upon the passage of the truck to the track section B, battery D will be short circuited, the relay 100 6 deenergized, and the armatures 10, 11 and 12 will drop, breaking the point of contact at 22 and closing the circuit at points 24 and 25. The circuit will now be closed through the signal conductor L, contacts 19 and 24 and 105 the ground G. Contact 25 will provide another path through insulated rail section B from the battery D, contact 25, conductors 27 and 15 through battery F, contact points 17, rail 8, back to battery D. Thus both 110 relays are deenergized while the truck is passing over rail section B. As soon as the train

has passed on, off the insulated rail sections, the short circuits will be destroyed, the relays will be energized again as their circuits are reestablished and their armatures will be returned to their normal condition as indicated in Fig. 1.

We will assume now that a train is approaching from the opposite direction or from the right of the figure. As the forward 10 wheels pass upon the rail section B, the battery D will be short circuited through the truck, the relay 6 deenergized to allow its armature to drop and break the connection at the point 22 and reestablish the contact at 15 the points 24 and 25. The circuit, however, will be broken at the point 19 leading to the ground and the signal will remain inoperative. When the truck passes on to the insulated section A and is partly on one section 20 and partly on the other, the same conditions will prevail as the circuit will be broken at 22 and the signal circuit will still remain open. This condition will continue until all the trucks have passed off the insulated section B. 25 As soon as this happens the relay 6 will be energized again attracting its armature and closing the circuit at point 22 and breaking it at point 24, and battery F will be short circuited but without result as the signal 30 circuit is broken at 24, consequently the signal will still be inoperative.

When the trucks have passed entirely off the rail section A, the relay 2 will return to its normal condition. It will thus happen 35 that when a train is moving over the track toward the right and passes the relays, the signal circuit will be closed and the signal operated, but when a train passes over the same track in the opposite direction the 40 signal circuit will be opened and the signal be inoperative.

I claim as my invention:

1. The combination, with a track having insulated rail sections and normally closed 45 relay circuits, of a normally open signal circuit and said relay circuits being arranged to close said signal circuit when a train is moving over said insulated rail sections in one direction and to allow said signal circuit 50 to remain open when a train is moving over said insulated rail sections in the opposite direction.

2. The combination, with the track rails having insulated rail sections A and B and a 55 battery D in circuit with said section B and the opposite rail, of a relay having a battery F in circuit with said rail sections A, a second relay in circuit with said rail section B and with the opposite rail, a contact point having 60 a ground connection in the path of the armature of said first named relay, a second contact point in the path of the armature of said second named relay, a conductor con-

necting said armatures, a signal circuit connected with said second contact point, 65 whereby when a truck passes on to said insulated sections from the left, said relays will be deenergized and said signal circuit closed through said contact points, substantially as described. 70

3. The combination, with the track rails having insulated rail sections, of a closed circuit relay connected with one of said rail sections, and deenergized upon the entrance 75 of a train upon said insulated track section, a second closed circuit relay connected with said second track section and deenergized by the passage of a truck on to said second insulated track section, a signal circuit normally open, and means whereby when said 80 second relay is deenergized said signal circuit will be closed to operate the signal, substantially as described.

4. The combination, with the track rails having insulated rail sections A and B on the 85 same side of the track, of a signal circuit normally open having a suitable signal, relay circuits normally closed and sources of electrical energy therefor and said relay circuits being arranged to be successively short circuited upon the passage of a train over said rail sections moving in one direction to close 90 said signal circuit and operate said signal and to allow said signal circuit to remain open when a train is moving over said insulated rail sections in the opposite direction, substantially as described. 95

5. The combination, with the track rails having insulated rail sections, of normally closed relay circuits arranged to be short circuited upon the passage of a train on to said insulated sections, a normally open signal circuit and means whereby said signal circuit will be closed and the signal operated upon the short circuiting of said relay circuits and 10 the deenergizing of their relays when a train passes over said insulated rail sections moving in one direction and whereby said signal will remain open when said relays are deenergized by the passing over said sections 11 of a train moving in the opposite direction.

6. The combination, with a track having normally closed relay circuits, of a normally open signal circuit, and said relay circuits being arranged to close said signal circuit when 11 a train is moving over said track in one direction and to allow said signal circuit to remain open when a train is moving over the track in the opposite direction, substantially as described. 12

In witness whereof, I have hereunto set my hand this 20th day of April, 1906.

EDWARD MCCLINTOCK.
